DISCHARGE MECHANISM FOR CONCRETE
MIXERSCharles F. Ball, Milwaukee, Wis., assignor to
Chain Belt Company, Milwaukee, Wis., a cor-
poration of Wisconsin

Application June 24, 1931, Serial No. 546,591

4 Claims. (Cl. 83—73)

This invention relates to discharge mechanism for concrete mixers and other similar agitating apparatus and has for one of its objects to provide a device of this character which will be simple in construction, comparatively inexpensive to manufacture and install and more efficient in use than those which have been heretofore proposed.

In my prior U. S. Patent No. 1,781,965 I have disclosed and claimed a concrete mixer of the truck or transit type in which the rotatable mixing drum is provided with spiral mixing blades or vanes which, when the drum is rotated in one direction assist in the mixing action and move the constituents longitudinally toward the forward end of the drum and away from the discharge opening which is located in the rear end wall. Upon reversal of the direction of rotation of the mixing drum these blades or vanes move the mixed concrete in the opposite direction, longitudinally toward the rear of the drum and toward the discharge opening. The drum is provided at its rear end adjacent the discharge opening with buckets, shown in my said patent as constituting extensions of the said mixing blades which, during the said reversed rotation, pick up the mixed concrete and deposit it into a discharge chute which normally is positioned outside of the drum but which during the discharge period is moved about a pivot to enter the discharge opening to a position where it may receive the concrete as it is dumped from the said buckets. The type of discharge just described is also commonly used in other forms of rotating drum concrete mixers such as small contractors mixers and street pavers.

The present invention has for its principal object to provide an improved construction which will take the place of the buckets above referred to and which will eliminate the necessity for the use of the swinging discharge chute heretofore commonly employed.

With the above and other objects in view which will appear as the description proceeds, the invention consists in the novel details of construction and combinations of parts more fully hereinafter described and particularly pointed out in the appended claims.

Referring to the accompanying drawings forming a part of this specification in which like reference characters designate like parts in all the views:—

Figure 1 is a side elevational view of a transit mixer of the general type shown in my said prior patent, certain of the parts being broken away and the mixing drum being shown in longitudinal section on approximately the plane indi-

cated by the line 1—1 of Figure 3 and provided with discharge mechanism constructed in accordance with the present invention;

Figure 2 is a rear end elevational view of the mixing drum shown in Figure 1, the end wall being partly broken away to more clearly disclose the pick-up or discharge mechanism;

Figure 3 is a transverse sectional view through the said drum, taken approximately on the plane indicated by the line 3—3 of Figure 1 and looking 10 in the opposite direction to Figure 2; and

Figure 4 is a fragmentary, horizontal sectional view through the discharge end of the drum, taken approximately on the plane indicated by the line 4—4 of Figure 3.

In the said drawings, 10 indicates generally a motor truck upon the chassis of which is mounted a mixing or agitating unit 11 which includes the rotatable mixing drum 12 driven in any suitable manner as by means of an independent motor contained in the housing 13, all as disclosed in my said prior Patent No. 1,781,965. The said drum is provided with a discharge opening 14 in its rear end wall 15 and is also provided upon its interior surface with the helical mixing blades or vanes 16 which move the concrete materials toward the front end of the drum when the latter is rotated in one direction, and reverse such movement when the drum is rotated in the opposite direction, as will be readily understood.

In place of the discharge buckets shown and described in my said prior patent, I provide a plurality, preferably two, pick-up elements 18, positioned adjacent and secured to the rear end 35 wall 15 of the drum by brackets or by welding, as may be desired. These pick-up and discharge elements are preferably stamped from sheet metal to provide a longitudinal wall 20 and a vertical wall 21 at substantially right angles to the wall 40

20. The elements are thus substantially L-shaped in cross section and together with the end wall 15 of the drum, form transversely extending troughs in which the wall 20 constitutes the bottom of the trough, and the wall 21 together with the end wall 15 of the drum constitute the side walls of the trough. The said pick-up elements are preferably substantially arcuate, as will be apparent from Figures 2 and 3, and extend from the outer shell 17 of the drum to the discharge opening 14 thereof.

The discharge end portions 22 of the said elements are disposed opposite to the discharge opening and the walls 21 are deflected as at 23 50

toward the said opening so that concrete or other material which may be picked up in the trough and which will be moved toward the said opening over the bottom wall 20 when the drum is rotated in a clockwise direction as viewed in Figure 3, will be diverted to and through the discharge opening 14 as will be readily understood from the drawings. The adjacent edges of the companion side walls 21 are turned outwardly at substantially right angles, as indicated at 24, to assist in this movement of the concrete through the discharge opening.

When the drum is rotated in a counterclockwise or mixing direction indicated by the left hand arrow in Figure 3, the mixing blades 16 will move the material away from the discharge opening 14 as previously described, and during such rotation no material will be picked up by the arcuate troughs 18. However, when the rotation of the drum is reversed, as indicated by the right hand arrow in Figure 3, the material will be moved by the blades 16 toward the discharge opening, and the troughs 18 will segregate and pick up portions thereof which during the inclination of the bottom walls 20 as the troughs are rotated will slide down the said troughs to the discharge opening 14 where it will be deflected by the angularly disposed portions 22 and 24 of the side walls 21 out through the said opening and into the discharging hopper 25. It will thus be seen that the contents of the drum may be quickly and efficiently discharged through the opening 14 without the necessity for the use of the usual discharge chute and its manual or power manipulation.

It will be noted from Figures 2 and 3 that the complementary end portions 22 and 24 of the two pick-up troughs 18 are arranged to substantially completely shield the discharge opening 14 against direct longitudinal movement of the material within the drum through such opening. In other words, the concrete mixture or the raw ingredients thereof when loaded into the drum are prevented from moving directly through the opening 14 in an axial direction by reason of the end portions 22 and 24 of the said troughs which in effect provide a transverse partition wall, past which the drum contents cannot find its way directly but only when picked up within the troughs and moved in a transverse direction substantially radially to the said opening where it is deflected longitudinally through the opening by the said deflected portions 22 and 24. This is of material importance in transit mixers where the usual practice is to load the drums much above the lowest point of the discharge opening circumference as it will prevent the material from passing through the opening and being lost in the event the usual discharge closure is not employed or has been inadvertently not put in place.

The invention has been shown and described in connection with a transit mixer, but this has been for illustrative purposes only, and it will be readily understood that it is equally susceptible of use in stationary, portable, and paving mixers.

While one form of the invention has been described it is obvious that those skilled in the art may vary the details of construction as well as the precise arrangement of parts without departing from the spirit of the invention, and therefore it is not wished to be limited to the above disclosure except as may be required by the claims.

What is claimed is:

1. In mixing and agitating apparatus, a receptacle having an end wall provided with a discharge opening; and transversely extending pick-up members adjacent said end wall terminating at said opening, for receiving and directing the contents of the receptacle transversely thereof to and through said opening, portions of the walls of said members being complementarily arranged adjacent said opening to provide a shield substantially completely closing said opening to direct longitudinal movement of the contents therethrough. 5

2. In mixing and agitating apparatus, a rotatable receptacle having an end wall provided with a discharge opening; and transversely-extending pick-up troughs adjacent said end wall for receiving and directing the contents of said receptacle transversely thereof to said opening, the discharge-end portions of the inner side walls 20 of said troughs being provided with extensions projecting into said opening and having angularly disposed members arranged back to back substantially diametrically of said opening, for deflecting the transversely moving material in the 25 troughs and directing it longitudinally through said opening.

3. In a truck mounted concrete mixer or agitator having a rotatable drum provided with a transverse end wall having an axial discharge opening, the body portion of said drum being provided with agitating blades arranged to move the contents of the drum longitudinally thereof in one direction or the other according to the direction of rotation of the drum, a plurality of 30 transverse pick-up troughs extending substantially radially along said transverse end wall from the side wall of the drum to said discharge opening for conveying the material to said opening when the drum is rotated in such direction as to cause its agitating blades to move said material toward said end wall, each of said troughs having a bottom and a side wall, the inner end portions of said walls being complementarily arranged adjacent said opening to completely shield the same against discharge of the material therethrough except by means of the troughs when the drum is rotated in the discharging direction. 35

4. In a truck mounted concrete mixer or agitator having a rotatable drum provided with a transverse end wall having an axial discharge opening, the body portion of said drum being provided with agitating blades arranged to move the contents of the drum longitudinally thereof in one direction or the other according to the direction of rotation of the drum, a plurality of 40 transverse pick-up troughs extending substantially radially along said transverse end wall from the side wall of the drum to said discharge opening for conveying the material to said opening when the drum is rotated in such direction as to cause its agitating blades to move said material toward said end wall, each of said troughs having a bottom and a side wall, the inner end portions of said walls being complementarily arranged adjacent said opening to completely shield the same against discharge of the material therethrough except by means of the troughs when the drum is rotated in the discharging direction. 45

5. In a truck mounted concrete mixer or agitator having a rotatable drum provided with a transverse end wall having an axial discharge opening, the body portion of said drum being provided with agitating blades arranged to move the contents of the drum longitudinally thereof in one direction or the other according to the direction of rotation of the drum, a plurality of transverse pick-up troughs extending substantially radially along said transverse end wall from the side wall of the drum to said discharge opening for conveying the material to said opening when the drum is rotated in such direction as to cause its agitating blades to move said material toward said end wall each of said troughs having a bottom and a side wall, the inner end portions of said walls being complementarily arranged adjacent said opening to completely shield the same against discharge of the material therethrough except by means of the troughs when the drum is rotated in the discharging direction, the said inner end portions 50 of said trough side walls having angular extensions projecting through said opening to deflect the material from its transverse path longitudinally through said opening. 55
